HERBERT G. UNDERWOOD, OF STAMFORD, CONNECTICUT, ASSIGNOR TO
H. H. FRANKLIN MANUFACTURING COMPANY, OF SYRACUSE, NEW
YORK, A CORPORATION OF NEW YORK.

CASTING APPARATUS.

No. 852,811.

Specification of Letters Patent.

Patented May 7, 1907.

Original application filed June 17, 1897. Renewed January 11, 1900, Serial No. 1,145. Divided and this application filed December 8, 1902. Serial No. 134,429.

To all whom it may concern:

Be it known that I, HERBERT G. UNDERWOOD, of Stamford, in the county of Fairfield and State of Connecticut, have invented a 5 certain new and useful Casting Apparatus, of which the following is a specification.

The invention forming the subject-matter of this present application is divisional of my prior application filed June 17, 1897, renewed 10 Jan. 11, 1900, Serial No. 1,145, and comprises certain novel combinations and constructions in casting apparatus, as hereinafter fully described and pointed out in the claims.

The accompanying drawings illustrate an 15 apparatus designed and chosen for explanation of this invention, and in these drawings: Figure 1 is a front elevation, partly in section, of the apparatus; and Fig. 2 is a side elevation of a slightly modified construction 20 of said apparatus.

A is a melting pot, or other source of supply for the material to be cast, said part A being shown as having a top or cover B; C is a cylinder or chamber supported by the top or 25 cover B within the pot A and the molten material therein, and provided with inlet- and outlet-ports c c'; D is a plunger actuated by a lever d for forcing the material from the cylinder or chamber C through the outlet-port 30 c'; and E is a substantially upright exit-port or nozzle communicating with the port c'.

The parts thus far described, comprise the means for supplying the material to be cast, and are each of suitable or desirable form, 35 size and construction.

The remaining parts of my apparatus form the mold - supporting and manipulating means.

In the illustrated embodiment of my invention, F is a supporting member, G a mold and J a clamping member. As shown, the member F is movable rectilinearly along a standard H, fixed relatively to the exit-port E, toward and from the exit-port or nozzle 45 E and an adjustable stop b, and is provided with a port or orifice f for registering with the part E, and with suitable engaging means, as rods F' having adjustable stops f'.

The mold G is composed of any desirable

number of sections or parts, here shown as 50 two, is mounted directly on the supporting member F, and is preferably provided with an ingate g opening from the face of the mold opposed to the supporting member F, and normally registering with the port or orifice 55 f. During the entrance of the material to be cast, said mold is firmly pressed rectilinearly, or in a right line, toward the opposing face of the member F and the exit-port E by the clamping member J and the movable means 60 connected thereto.

The clamping member J is movable rectilinearly toward and from the supporting member F, being usually provided with openings or guides for receiving the standard 65 H and the rods F'. When the clamping member is in its operative position, the opposing faces of said clamping member and the stops f' are considerably separated, and, consequently, the member J is free to move 70 independently of the support F until the opposing faces of the parts J f' are engaged, whereupon the supporting and clamping members F J move together. The clamping member J is here shown as movable into and 75 out of its operative position by a lever N pivoted at M and provided with an arm K movable into engagement with a stop i, and connected by a link K' to said clamping member. When the clamping member J is in its 80 operative position, the pivot l for connecting the arm K and the link K' is alined with the pivot M and the pivot for connecting the other end of the link K' to the clamping member J, thus firmly locking said member 85 J in position during the entrance of the material to be cast.

In the illustrated construction of my invention, I use two standards H, arms K, and links K', but it will be obvious to those skilled 90 in the art, that one of each of said standards, arms and links may be omitted if desired, as illustrated in my pending application, Serial No. 1,145. In Fig. 1, the standards H are supported at their lower ends by the top or 95 cover B, and serve to support at their upper end, a part I to which the lever N is pivoted, but in Fig. 2, the standards H and the lever

N, are supported by an arm B² projecting laterally from a standard B³, rising from the top or cover B.

In the use of this invention, the two sections or parts of the mold G are detachably engaged, respectively, with the supporting and clamping members F J, the free end of the lever N is moved downwardly, thus permitting the supporting and clamping members to move downwardly toward the exit-port E until the supporting member reaches the limit of its downward movement, whereupon the clamping member moves downwardly independently of the supporting member until the mold is closed and the arm K engages the stop i. The clamping member J then firmly presses the mold as a whole toward the contiguous face of the supporting member F and the exit-port or nozzle E, and the pivots l lock the clamping member J in its operative position. After the formation of the cast article in the mold, the free end of the lever N is raised, elevating the clamping member J, and the section of the mold secured thereto independently of the supporting member F and the remaining portion of the mold and permitting access to the cast article. During the upward movement of the clamping member J, the opposing faces of the member J and the stops f' are engaged, whereupon the supporting member moves upwardly with the part J withdrawing the port f from the exit-port or nozzle E. These several operations can obviously be completed with minimum effort and maximum rapidity.

The construction and operation of my casting apparatus will now be readily understood upon reference to the foregoing description and the accompanying drawing, and it will be obvious that more or less change may be made in the construction and arrangement of the parts thereof, without departing from the spirit of my invention.

Having thus fully described my invention, what I claim as new and desire to secure by Letters Patent, is:—

1. In a casting apparatus, a source of supply for the material to be cast, an exit-port for communicating with the source of supply, a sectional mold having an ingate for communicating with the exit-port, means for forcing the material from the exit-port through the ingate into the mold, a supporting member for the mold movable rectilinearly toward and from the exit-port, and a clamping member connected to a section of the mold, said clamping member being movable rectilinearly toward and from the supporting member a limited distance and being movable with the supporting member, and means for moving the clamping member for operating the same into and out of its oper-

ative position, substantially as and for the purpose set forth. 65

2. In a casting apparatus, a source of supply for the material to be cast, an exit-port for communicating with the source of supply, a sectional mold having an ingate for communicating with the exit-port, means for forcing the material from the exit-port through the ingate into the mold, a supporting member for the mold, a clamping member connected to a section of the mold, means connecting the clamping member to the supporting member for moving the supporting member with the clamping member and permitting a limited movement of the clamping member independently of the supporting member, and means for moving the clamping member into and out of its operative position, substantially as and for the purpose described. 75

3. In a casting apparatus, a source of supply for the material to be cast, an exit-port for communicating with the source of supply, a sectional mold having an ingate for communicating with the exit-port, means for forcing the material from the exit-port through the ingate into the mold, a supporting member for the mold movable toward and from the exit-port and provided with engaging means, a clamping member connected to one of the sections of the mold and movable into and out of operative engagement with said engaging means, and movable means connected to the clamping member for operating the same, substantially as and for the purpose specified. 85

4. In a casting apparatus, a source of supply for the material to be cast, an exit-port for communicating with the source of supply, a sectional mold having an ingate for communicating with the exit-port, means for forcing the material from the exit-port through the ingate into the mold, a standard fixed relatively to the exit-port, a supporting member for the mold guided along the standard, a clamping member guided along the standard, means connecting the clamping member to the supporting member for moving the supporting member with the clamping member and permitting a limited movement of one of said members independently of the other, and movable means connected to one of said members for operating the same, substantially as and for the purpose specified. 95

5. In a casting apparatus, a source of supply for the material to be cast, an exit port for communicating with the source of supply, a sectional mold having an ingate for communicating with the exit-port, means for forcing the material from the exit-port through the ingate into the mold, means for moving one of the sections toward and from

the exit port, and means inactive during the initial movement of the first section coacting with the second section during the final part of the movement of the first section to move the second section with said first section, substantially as described.

5 In testimony whereof, I have hereunto signed my name in the presence of two attest-

ing witnesses at New York in the county of New York in the State of New York this 4th 10 day of December, 1902.
